EUGENE MCEWEN, OF INDIANAPOLIS, INDIANA

CAR LOADING ROLLER

Application filed July 17, 1929. Serial No. 379,010.

This invention relates to a device adapted to be positioned in door openings of freight cars and the like for the ready and economical loading and unloading of the car with material such as lumber.

The chief object of the invention is to provide a door opening with mechanism that may be readily applied thereto to facilitate and expedite the loading and unloading through said opening and with a minimum of parts or material.

The chief feature of the invention consists in the rolling surface provided for supporting the articles to be loaded or unloaded and another chief feature consists in the ready mounting and demounting of the attachment including the aforesaid supporting surface.

The full nature of the invention will be more clearly understood from the accompanying drawings and the following description and claims:

Fig. 1 is a side elevation of a steel box car loaded with lumber and with the invention applied thereto. Fig. 2 is an enlarged longitudinal sectional view through one form of the device. Fig. 3 is a similar view of a modified form of a portion of the device. Fig. 3a is a similar view of the adjusting end of the device shown in Fig. 3. Fig. 4 is a similar view of a still further modified form of the device. Fig. 5 is a longitudinal sectional view through a still further modified form of the device. Fig. 6 is a similar view of a portion of a still further modified form of the device.

In the drawings 10 indicates a freight car having the door opening 11 closed by the doors 12 or by a single door. Positioned in the car is the lumber 13. A plank 14 is shown positioned upon the invention.

When a steel car is to be loaded or unloaded, planks or wooden bearing members 15 are positioned at each side of the opening and the invention engages the same instead of the metal frame of the door opening.

When a wooden box car is to be loaded or unloaded the invention is directly applied thereto.

The invention includes a pair of anchoring members or plates 16 each of which has a corrugated surface 17 preferably flat and the corrugations may be of intersecting character or annular or individual projections. In brief, the flat face 17 is roughened or suitably formed for bearing engagement. If desired, the flat face may be provided with a penetrating prong 18 and herein the prong 118 is shown considerably larger than the prong 18. Prong 118 is forced into the member 15 with quick thrust and then the mechanism is leveled by eye and the prong 18 is caused to imbed in the opposite member 15 with the device interposed therebetween.

Each member 16 includes a neck 19 defining a central socket 20 that terminates in a semi-spherical head portion 21 which receives the head 22 of substantially ball formation. A set screw 23 prevents separation of the anchoring base and the ball supported thereby, but permits relatively free universal action for mounting and demounting of the device.

Extending from one base member and preferably the one including the prong 118 is a shaft 24 connected by the reduced neck 25 to the ball portion 22 mounted in the socket of the base member. Shaft 24 is threaded at its opposite end as at 26. A tubular member 27 is provided with a similarly threaded socket 28 which receives the threaded end 26 of shaft 24. Extending transversely of the socketed member 27 and slidably supported thereby is the head turning handle member 29. The socketed member 27 is connected by the neck portion 30 to the spherical head 22 supported by and in the base or anchorage including the short prong 18. As the handle 29 is rotated the two bases move toward and away from each other, depending upon the direction of rotation and through

the instrumentality of the threaded connection described.

In Fig. 2 the simplest form of the invention is illustrated and the same includes a tubular cylindrical surface 31 which is rollably supported upon the shaft 24 through the antifriction roller constructions 32 positioned at each end. Rollers 32 are maintained against axial separation by washers 33 and the set screw secured collars 34, which washers and collars also secure the tube 31 against relative axial movement from the shaft. Inward or approaching movement of the antifriction rollers 32 is prevented by a collar construction 35 similarly secured to the shaft and of course, of a diameter sufficient to provide clearance between the same and the tube 31. Any number of antifriction constructions may be intermediately positioned within the tubular surface 31 and suitably secured against axial displacement by collar constructions 35.

In Fig. 3 a modified form of the invention is illustrated which differs from that shown in Fig. 2 in two particulars,—to-wit: a tubular surface is divided transversely and in place of the inclosed roller retaining collars there is provided spacing tubes. In said figure, a plurality of short tubular surfaces 131 are each provided at each end with an antifriction roller construction 132 and axial movement thereof is limited by the washer 133 also limits axial movement of the tubular surface 131. Instead of said inclosed collars a concentric tube 135 secures the desired spaced relation between antifriction roller cages. The usual end washers and set collars may be employed. Herein the rolling surface is illustrated as comprised of three sections although the number thereof may be varied as desired or required.

In Fig. 5 there is illustrated a form of the invention which is a departure intermediate from the form shown in Figures 2 and 3 in that the inclosed antifriction roller constructions 232 are maintained in spaced relation against inward movement by set collars 235. In this form of the invention the tubular rolling surface 231 is divided transversely and the sections and the antifriction constructions are maintained in predetermined relation by the washers 233 interposed therebetween. The end of the construction is retained in position in the usual manner by an end washer 233 and a set collar 234.

In Fig. 4 a still further modified form of the invention is illustrated and in this form of the invention the rolling surface is shown divided transversely and includes a plurality of tubes 331 separated by the washers 333 which instead of extending inwardly to the supporting shaft in this instance roll upon an antifriction roller construction 332 which supports adjacent ends of adjacent tubular sections 331. In this form of the invention,

movement of the inclosed roller constructions toward and away from each other and within the tubular rolling surface is prevented by the set collars 335. Complete separation by reason of axial movement toward the ends is prevented by the usual end washers 433 and the set collars 434.

A further modified form of the invention from that shown in Fig. 4 is shown in Fig. 6 wherein the two opposed inclosed set collars are eliminated and spacing tubes 535 such as shown at 135 in Fig. 3 are substituted for the same.

Another modification shown in Fig. 6 consists in substituting for the said end collars another suitable or equivalent anchorage such as a tapered pin 534.

In the present invention it will be readily apparent that it can be quickly applied to or detached from a car door opening and except for the threaded connection all of the parts are permanently connected together. The threaded connection permits of the desired extensibility or contraction in the length of the device for mounting the same in all door openings within the range of the device. The present invention eliminates the employment of rigid bracing across a car door opening such as heretofore has been employed in the loading and unloading of freight cars, particularly with lumber. The employment of this device eliminates not only the lumber and nails heretofore required to provide such a framework but also eliminates the labor necessary to build and tear down such a supporting framework. The employment of this device in addition permits lumber to be handled with greater ease and, therefore, facilitates the expeditious loading and unloading of a car of lumber. Furthermore, the sectionalized form of device permits long pieces of lumber to be easily manipulated into and out of the car.

The invention claimed is:

1. A device of the character described including a pair of axial applying pressure seating bases, longitudinally extensible means, a universal joint connection between each end of the means and each of said bases, and a rolling surface coaxially supported by said means.

2. A device of the character described including a pair of axial applying pressure seating bases, longitudinally extensible means, a ball and socket connection between each base and said means, and a rolling surface coaxially supported thereby.

3. A device of the character described including a shaft, a member threadedly associated therewith for longitudinal adjustment thereon, means carried by the opposite ends of the threadedly associated members for supporting the same, tube means concentric with said shaft, and a roller construction associated with the ends of said tube

means for antifrictionally supporting said tube means upon said shaft.

4. A device of the character described including a shaft, a member threadedly associated therewith for longitudinal adjustment thereon, means carried by the opposite ends of the threadedly associated members for supporting the same, tube means concentric with said shaft, and a roller construction associated with the ends of said tube means for antifrictionally supporting said tube means upon said shaft, said tube means including a plurality of tubes arranged in end to end tubular formation forming an elongated rolling surface.

In witness whereof, I have hereunto affixed my signature.

EUGENE McEWEN.
